CLAIM

The ornamental design for an arrow rest support guide, as shown and described.

DESCRIPTION

FIG. 1 is a perspective view of an arrow rest support guide made in accordance with my design;

FIG. 2 is a top plan view thereof;

FIG. 3 is an elevational front side view thereof;

FIG. 4 is an elevational left side view the right side view being a mirror image thereof; and,

FIG. 5 is a bottom plan view thereof.

The characteristic feature of the design resides in the triangular notch cut in the opposing sides of the head supported by the pin of the support guide.
